UNITED STATES PATENT OFFICE.

PATRICK J. HANLEY, OF AMESBURY, MASSACHUSETTS.

DAMPER AND HEAT-DEFLECTOR.

SPECIFICATION forming part of Letters Patent No. 574,480, dated January 5, 1897.

Application filed March 9, 1896. Serial No. 582,310. (No model.)

To all whom it may concern:

Be it known that I, PATRICK J. HANLEY, a citizen of the United States, and a resident of Amesbury, in the county of Essex and State 5 of Massachusetts, have invented new and useful Improvements in Dampers and Heat-Deflectors, of which the following, taken in connection with the accompanying drawings, is a specification.

10 This invention relates to an improved damper and heat-regulator for smoke-conducting pipes of stoves, furnaces, and other heat-generators, and it is carried out as follows, reference being had to the accompanying 15 drawings, wherein—

Figure 1 represents a central longitudinal section showing the damper closed. Fig. 2 represents a similar longitudinal section showing the damper open. Fig. 3 represents a top 20 plan view of Fig. 2, and Fig. 4 represents a longitudinal section on the line 4 4 shown in Fig. 3.

Similar letters refer to similar parts wherever they occur on the different parts of the 25 drawings.

A represents the smoke-pipe of a stove, furnace, or other suitable heat-generator, as usual. In the wall of said smoke-pipe is journaled the damper key-bar B, preferably 30 slightly curved, as shown, and provided at one end with a handle b for turning and adjusting the position of the damper within the smoke-pipe as may be required. To the key-bar B is secured a conical cup-shaped heat-deflector C, the upper side of which serves as 35 a downward-draft-controlling device.

D is a central spindle secured in its upper end to the key-bar B and deflector C, as shown, and to the lower end of said spindle is secured 40 a conical deflector E, similar to the one C at the upper end of the spindle D, as shown in the drawings. On the spindle D is longitudinally movable and adjustable the centrally-perforated annular damper F, the outer edge 45 of which fits loosely within the smoke-pipe A, as shown.

f is the central perforation in the annular damper F, which perforation in practice is made somewhat smaller in diameter than the

outer edge of the lower conical deflector E, as 50 shown, so as to cause the smoke-pipe A to be closed when the annular damper F is lowered in contact with the upper edge of the conical deflector E, as shown in Fig. 1.

In practice I prefer to attach to the annular 55 damper F a bail or cross-bar F', which is guided on the spindle D, as shown. Any suitable device may be employed for actuating the damper F, and in the drawings I have shown for this purpose a lever G, pivoted at 60 its outer end at g to the key-bar B and loosely connected at its inner end to the bail or bar F', as shown. The lever G is provided beyond its fulcrum g with an extension or handle G', adapted to be operated by hand or suitably 65 connected to an automatic device of any suitable or well-known construction, if so desired.

The operation is as follows: When the device is in the position shown in Figs. 2 and 4, the heat is deflected by coming in contact 70 with the lower deflector E, at the same time permitting the smoke and gases to pass upward through the central perforation in the annular damper F, and coming in contact with the deflector C a portion of the heat is 75 deflected and the smoke and gases permitted freely to escape. The upper deflector C serves also to prevent a downward draft through the smoke-pipe A. By adjusting the damper-plate F relative to the deflector E (or said deflector toward the said damper-plate F) the damper-opening may be more or less adjusted and entirely closed by bringing said deflector and damper-plate in close contact, as shown in Fig. 1. The damper may be fully opened 80 by turning the bar B and its connecting parts one-fourth of a revolution.

What I wish to secure by Letters Patent and claim is—

1. In a damper a key-bar journaled in the 90 smoke-pipe a central spindle secured to such bar and having a conical deflector C attached to its upper end combined with a lower deflector E and annular damper F one of said parts being adjustable to and from the other 95 and means for adjusting such parts substantially as and for the purposes set forth.

2. In a damper a key-bar journaled in the

smoke-stack and having a spindle D provided at its upper and lower ends with conical deflectors C E in combination with an adjustable annular damper F, and a pivoted lever 5 G connected to the said damper F substantially as and for the purpose set forth.

In testimony whereof I have signed my

name to this specification, in the presence of two subscribing witnesses, on this 26th day of February, A. D. 1896.

PATRICK J. HANLEY.
